(57) **CLAIM**

The ornamental design for a cake topper, as shown and described.

DESCRIPTION

FIG. 1 is a front view of a cake topper showing my new design;

FIG. 2 is a rear view of the cake topper;

FIG. 3 is a right side view of the cake topper;

FIG. 4 is a left side view of the cake topper;

FIG. 5 is a top view of the cake topper;

FIG. 6 is a bottom view of the cake topper; and,

FIG. 7 is a bottom front side perspective view of the cake topper.

The broken lines are illustrative of portions of the cake topper forming no part of the claimed design.
